UNITED STATES PATENT OFFICE.

WILLIAM EVENSEN, OF CHICAGO, ILLINOIS, ASSIGNOR TO GOSS PRINTING PRESS COMPANY, A CORPORATION OF ILLINOIS.

PRINTING-PRESS INKING MECHANISM.

Application filed July 2, 1923. Serial No. 648,984.

The invention relates to printing presses, and more particularly to printing press inking mechanisms, and especially to a novel ductor roll actuating and regulating or controlling mechanism.

Objects and advantages of the invention will be set forth in part hereinafter, and in part will be obvious herefrom, or may be ascertained by those skilled in the art by practicing the invention.

The invention consists in the novel parts, constructions, arrangements, combinations and improvements herein shown and described.

15 The accompanying drawings, referred to herein and constituting a part hereof, illustrate one embodiment of the invention, and together with the description serve to explain the principles thereof.

20 Of the drawings:—

Fig. 1 is a side elevation of a portion of the inking mechanism of a printing press which exemplarily embodies the invention; and

25 Fig. 2 is a view, partly in top plan, and partly in horizontal section on the line 2—2 of Fig. 1.

The invention is shown applied to a rotary printing press and finds its chief usefulness and most extensive application in connection with this kind or class of printing presses. One of the very important factors in connection with the proper inking of the printing plates or like printing instrumentality requires that there shall be a continuous, adequate, uniform and otherwise satisfactory and efficient supply of ink thereto. One of the chief factors in securing such an adequate and satisfactory inking supply and action is the proper mounting and control of the ductor roll, whereby variations in size, or otherwise, therein from various causes, such as wear, or shrinkage of the roll, may be compensated for by proper regulation of the mechanism.

45 The present invention is directed to the foregoing purpose, and with this end in view it embodies means for varying the extent or location of the path of travel or reciprocation of a ductor roll, and also for controlling and varying this path with respect to both the fountain ink roller and the inking drum between which the ductor roll oscillates or vibrates.

More particularly, means are provided for varying the length of the path of travel of the ductor roller, for varying the terminal points of this path of travel, irrespective or independently of the regulation of the length thereof, that is, means are provided for varying the length or amplitude of the path of travel and in conjunction therewith the relative position or relation of the path of travel to both the fountain ink roller and the ink drum.

Referring now in detail to the accompanying drawings, only the parts of a printing press inking mechanism which are directly involved in the present invention are shown. It will be understood that a complete inking mechanism will be provided, which may be of any known or suitable form for cooperation in the particular kind of press and for the particular kind of work to be done.

In said embodied form, the general frame of the printing press is indicated by the reference numeral 1. An inking fountain 2, which may be of any known or suitable form, is provided, and is mounted upon the press frame. In cooperation with the ink fountain is a fountain roller 3, the shaft 4 of which is conveniently journaled at 5 in the walls of the ink fountain. The inking roller may be of any known or suitable form, and may be actuated by any known or suitable form of actuating mechanism. For instance, the roller may be either of the intermittently rotated or of the continuously rotated type, as may be preferred. The mechanism is especially capacitated, however, for use with a continuously rotating fountain roller.

An inking drum 6 is shown, having its shaft 7 journaled in bearings 8, carried in the frame 1 of the printing press. It will be understood that the inking drum 6 cooperates with various other elements or mechanisms to convey the ink to the plates on the form cylinder, which additional mechanism is not shown herein, and may be of any convenient or desired form.

A ductor roller 10 is provided, having its shaft 11 journaled in bearings 12, carried on the upper end of a pair of reciprocating arms 13, which arms are fixed to a shaft 14, the shaft 14 being journaled at 15 in the machine frame. The shaft 14 projects outwardly from the frame at one side, and

there is fixed to this end of the shaft a crank arm 16. A spring 17, of any convenient form and in any convenient location may be used to impel the ductor roll to the 5 fountain roller and to cause cam roller 48 to follow cam 49.

In the present embodied form of the mechanism, the regulating and controlling mechanism for the movements and the position of 10 the path of travel of the ductor roll are preferably located between the arm 16 and the actuating mechanism therefor. As so embodied, a rod or link 20 is pivoted to the arm 16 at 21, and is preferably provided medianly 15 with a turn-buckle or other length-regulating device 22. At its opposite end, rod 20 is pivotally connected to a pin 24, carried in and slideable along a bell crank lever 26 to vary the length of the path of travel 20 of the ductor roller. Pin 24 projects through and is slideable along a slot 25 formed in the bell crank lever 26 and the lever is pivotally mounted at 27 on the machine frame.

25 Pin 24 is integral with, or is fixed to, a block 32 bearing against and slideable along the side of the bell crank lever 26 already referred to. Suitable friction washers 33 and 34 are provided at either side of the rod 30 20 on the pin 24, and a nut 35 serves to keep the parts in place.

To best effect the purposes already broadly stated, the slot 25 in the bell crank lever 26 is of arcuate form, and is preferably in 35 radial relation to the pivot point 21 of the rod 20 upon the arm 16. Means are provided for sliding the pin 24 to and fro along the slot 25 and for exactly positioning it and maintaining it in the desired position along 40 the slot.

By this movement the length of the path of travel of the ductor roll may be varied; that is, it may be increased by moving the pin 24 away from the pivot point 27 of the bell-crank lever, or it may be shortened by moving the pin 24 toward the pivot point 27, of the bell crank lever. It will be clear that due to the arcuate slot 25 and its radial relation to the pivot point 21, this lengthening or shortening of the path of travel of the ductor roll 10, may be effected without 45 at the same time moving the ductor roll; that is, without changing its relation to either the fountain roller or ink drum except as this may be affected by the lengthening or shortening of its path of travel 50 equally at both ends.

If the ductor roll has shrunk so that it is 60 of less diameter, by moving the pin 24 away from the pivot point 27 of bell crank lever 26, the path of travel or reciprocation of the ductor roller 10 will be lengthened symmetrically at both ends. Its relation to the ink fountain roller 3 and to the ink drum 6 65 will be maintained unchanged, and the de-

gree of pressure on each will be maintained, and such change in size of the ductor roller will be compensated for. When a new roller is put in, the pin 24 may be accurately moved toward the pivot 27 and the conditions of 70 operation of the two rollers and the ink drum be maintained unchanged.

As already stated, the relative positions of the path of travel or reciprocation of the roller relative to the fountain roller 3 or the 75 ink drum 6 may be varied as desired. That is, the path of travel may be lengthened toward the fountain roller or toward the ink drum so as to vary the pressure or other 80 cooperation of the ductor roller with either of these at will, without changing the pressure or cooperation with the other.

This may be effected by means of the turn-buckle 22. That is, if the rod or link 20 be shortened, this would lengthen the path of 85 travel of the ductor roller 10 toward the ink drum 6 and cause under given conditions, greater pressure of the ductor roller upon the drum.

On the other hand, if the turn buckle 22 90 be turned to lengthen the link 20, the path of travel of the ductor roller 10 toward the fountain roller 3 would be lengthened, and it will exert greater pressure upon the fountain roller. It will be clear that by the 95 conjoint regulation or positioning of the pin 24 and the lengthening or shortening of the link 20 by the turn-buckle 22 any exact desired cooperation of the ductor roller with both the fountain roller 3 and the ink drum 100 6 may be effected as desired.

Referring to the embodied form of means for positioning, and regulating the position of, the pin 24 in the slot 25, as embodied, the slideable block 32 is internally screw-threaded 105 to receive a screw-rod 41. Screw-rod 41 is journaled at 42 in a block 43, which is in fixed position on the outer end of the bell-crank 26. Block 43 is fixed to a pin 44, which projects through a corresponding hole 110 in the outer end of the bell crank lever 26. This is held in place by a nut 40 screwed thereonto. Screw-rod 41 is preferably provided with a hand-wheel 45 on one side of the block 43, and it has a shoulder 46 on the opposite side of the block to maintain the screw-rod longitudinally in fixed position in the block 43, while permitting the rod to rotate freely.

In the embodied form of actuating means for the bell-crank lever 26, the arm 47 of the lever is provided with cam roller 48, which roller runs on a sliding cam 49, which cam is mounted on a carrier block 50. The block 50 is slidably mounted in a pair of guideways 51, on a bracket 52, mounted at 53 upon the machine frame. Retaining strips 54 and 55 keep the cam and its carrier block 50 in position in the guideways. The cam 49 is shaped to give the upward movement to 120 125 130

bell crank lever 26, thereby to the ductor roller and provides a dwell therefor at either end of its movement.

Means are provided for varying the position of cam 49 to vary the time or place of the dwell of the ductor roller, and as embodied, the carrier block 50 is provided with a rearwardly extending lug or projection 58, which is internally threaded to receive the screw-threaded end 59 of the actuating rod 60, which latter is operated by any suitable part of the printing press mechanism. The nuts 61 and 62 are provided to hold the carrier block in desired position on the rod 60. A turnbuckle 64 is provided in rod 60, whereby the rod may be either lengthened or shortened to change the position of the cam relatively to its actuating means.

20 By the variable positioning of the actuating cam 49 relatively to its shaft 60, which is preferably effected by means of the turnbuckle 64, the dwell of the ductor roller on either the fountain roller or the ink drum 25 may be regulated as desired. This is especially useful and desirable with a fountain roller with a continuous feed or rotation. In this way the period during which the ductor roller is in contact with the fountain roller or the ink drum may be regulated as desired.

The invention in its broader aspects is not limited to the specific mechanisms shown and described but departures may be made therefrom within the scope of the accompanying claims without departing from the principles of the invention and without sacrificing its chief advantages.

What I claim is:—

40 1. In a printing press inking mechanism having, in combination, an ink fountain roller, an ink drum and a ductor roll oscillatable therebetween, means for oscillating said ductor roll including a lever member and a link member pivotally associated therewith, and means for varying the path of oscillation of said ductor roll including an arcuate guideway on one of said members and means for variably positioning the other member in said arcuate guideway.

45 2. In a printing press inking mechanism having, in combination, an ink fountain roller, an ink drum and a ductor roll oscillatable therebetween, means for oscillating said ductor roll including a lever and a link pivotally associated therewith, means for varying the path of oscillation of said ductor roll including an arcuate guideway on said lever and means operable while the press is running for variably positioning the pivot of said link in said guideway.

50 3. In a printing press inking mechanism having, in combination, an ink fountain roller, an ink drum and a ductor roll oscillatable therebetween, means for oscillating

said ductor roll including a lever and a link pivotally associated therewith, a second pivot at the other end of said link, and means for varying the path of oscillation of said ductor roll including an arcuate slot formed 70 in said lever and curved about said second pivot at a center, and means for variably positioning said link with respect to said arcuate slot.

4. In a printing press inking mechanism 75 having, in combination, an ink fountain roller, an ink drum and a ductor roll oscillatable therebetween, means for oscillating said ductor roll including a lever and a link pivotally associated therewith, means for varying the location of the path of oscillation of said ductor roll, and means for varying the length of said path including an arcuate guideway on said lever, and means for variably positioning the pivot of said 80 link therealong.

5. In a printing press inking mechanism having, in combination, an ink fountain roller, an ink drum and a ductor roll oscillating therebetween, means for oscillating 85 said ductor roll including a lever and a link pivotally associated therewith, means for varying the location of the path of oscillation of said ductor roll, and means for varying the length of said path equally at each 90 end thereof including an arcuate guideway on said lever, and means for variably positioning the pivot of said link therealong.

6. In a printing press inking mechanism 95 having, in combination, an ink fountain roller, an ink drum and a ductor roll oscillatable therebetween, means for oscillating said ductor roll including a lever and a link pivotally associated therewith, and means for varying the path of oscillation of said 100 ductor roll including an arcuate guideway on said lever and means including a rotatable pivoted member for variably positioning the pivot of said link therealong.

7. In a printing press inking mechanism 105 having, in combination, an ink fountain roller, an ink drum and a ductor roll oscillatable therebetween, means for oscillating said ductor roll including a lever and a link pivotally associated therewith, and means for varying the path of oscillation of said ductor roll including an arcuate guideway on said 110 lever and means including a rotatable pivoted member operable while the press is running for variably positioning the pivot 115 of said link therealong.

8. In a printing press inking mechanism 120 having, in combination, an ink fountain roller, an ink drum and a ductor roll oscillatable therebetween, means for oscillating said ductor roll including a lever and a link pivotally associated therewith, means for varying the location of the path of oscillation of said ductor roll, and means for varying the length of said path equally at each 125

end thereof including an arcuate guideway on said lever and means including a rotatable pivoted member operable while the press is running for variably positioning the pivot of said link therealong.

9. In a printing press inking mechanism having, in combination, an ink fountain roller, an ink drum and a ductor roll oscillatable therebetween, means for oscillating said ductor roll including a lever and a link pivotally associated therewith and having a second pivot at its other end, means for varying the location of the path of oscillation of said ductor roll, and means for varying the length of said path equally at each end thereof including an arcuate guiding slot in said lever and curved about said second pivot as a center, and means including a rotatable pivoted member for variably positioning said link with respect to said slot without moving said ductor roll.

10. In a printing press inking mechanism having, in combination, an ink fountain roller, an ink drum and a ductor roll oscillatable therebetween, means for oscillating said ductor roll including a lever and a link pivotally associated therewith, a cam for actuating said lever, means for varying the length of the path of oscillation of said

ductor roll including an arcuate guideway on said lever and means operable while the press is running for variably positioning the pivot of said link therealong, and means for varying the dwell of said ductor roll at each end of its path of oscillation including a rotatable member for moving said cam with respect to said lever.

11. In a printing press inking mechanism having, in combination, an ink fountain roller, an ink drum and a ductor roll oscillatable therebetween, means for oscillating said ductor roll including a lever and a link pivotally associated therewith, a cam for actuating said lever, means for varying the length of the path of oscillation of said ductor roll including an arcuate guideway on said lever and means including a pivoted rotatable threaded member operable while the press is running for variably positioning the pivot of said link therealong, and means for varying the dwell of said ductor roll at each end of its path of oscillation including a rotatable member for moving said cam with respect to said lever.

In testimony whereof, I have signed my name to this specification.

WILLIAM EVENSEN.
